BOTTLE AND OTHER LABELING MACHINE.

Filed Aug. 9, 1929

UNITED STATES PATENT OFFICE

PERCIVAL JOHN PURDY, OF LONDON, ENGLAND

BOTTLE AND OTHER LABELING MACHINE

Application filed August 9, 1929, Serial No. 384 545, and in Great Britain October 24, 1928.

This invention relates to bottle and other labeling machines, and refers more particularly to machines of the type described in United States patent specification No. 5 998,664 in which a magazine is provided for the labels from which labels, which previously have adhesive applied to a certain part or parts thereof, are removed by so called "pickers" which also act to apply adhesive 10 to other parts of the label, and applied by said pickers to the bottle, a picker arm acting to apply the label to the bottle. As at present generally constructed in machines of this type the article, a bottle for example, is 15 placed by hand on a support where it remains whilst wipers act to complete the application of the label.

The present invention has for its object certain improvements according to which the 20 bottle or other article is automatically presented to the machine, and further provides means for completing the application of the label, which means are not directly associated with the labeling members of the machine itself.

According to one form of this invention an endless band or belt running transversely of the machine is provided, which belt may receive an intermittent movement through 30 geneva-stop or other suitable mechanism which may be driven independently of the main machine. The belt is provided with suitably spaced cradles or other supports for the bottles, and said belt carries the articles 35 into and out of position for the application of the labels. In order to complete their application there is or are provided one or more wipers, the action of which is suitably timed to cause them, when the belt is at rest, to come 40 into action and wipe or press the labels. In addition to the wipers, printing or dating means may be provided.

The action of the wipers or the like may 45 conveniently be secured by means of lever or other mechanism actuated by cam or other mechanism mounted upon a shaft from the main machine or otherwise.

The invention may be applied either to 50 machines where the bottles or other articles are placed horizontally, or where same are

in a vertical position whilst the labeling is effected. By means of the invention, by duplicating the necessary parts, two or more articles may be simultaneously moved and labeled.

The form of the "wipers" may be varied as desired, for instance these may be in the form of discs, rollers, or plungers carrying the wipers, which may either have a reciprocal motion towards and away from the articles, or they may be relatively fixed or spring mounted.

Instead of being connected to and carrying the articles automatically to the labeling position, the intermittently actuated conveyor with the wipers may be used as an auxiliary to an existing labeling machine to further wipe and so ensure the better attachment of the labels.

In order that the invention may be the better understood the following drawings are appended in which:—

Fig. 1 is a front elevation of a device constructed in accordance with one form of the present invention as applied to the labeling of bottles.

Fig. 2 is a plan.

Fig. 3 is a view as seen from the left hand end of the device.

Fig. 4 is a view to a larger scale showing certain details.

Referring to the accompanying drawings, 1 indicates generally a labeling machine of the type described in United States patent specification No. 998,664, which comprises a 35 label magazine 2; picker blades 3 carried upon a vertically reciprocating frame 4; a paste roller 5 carried by arms 6 by means of which it is periodically moved out of contact with a second roller 7, which rotates in a paste trough 8, onto and across the picker blades 3; and a picker arm 9.

The frame of the device for presenting the bottles to the labeling machine comprises two pairs of uprights 10, 10^a, which carry at their upper ends horizontal members 11, 11^a, respectively.

Disposed at each end of the members 11, 11^a, are sprocket wheels 12, 12^a arranged in spaced relationship to each other, and carried

upon shafts 13, 13^a which extend between the said members and are journaled in bearings 16, 17, 18 and 19 carried upon the respective ends of the members 11, 11^a.

5 20, 20^a indicate endless chains which pass around the sprocket wheels 12, 12 and 12^a, 12^a, and formed integral with the links 21, of each of which chains are substantially V shaped supporting bodies 22 so arranged that the 10 bottles, indicated by α may be supported upon them so that their longitudinal axes are disposed transversely of the chains, as shown in Fig. 3, suitable tie rods 23 being provided at suitable intervals between both chains.

15 The main driving shaft of the device, indicated by 24 and disposed at a point between the members 11, 11^a, and slightly below the same, is carried in bearings 25, 26 formed integral with brackets 25^a, 26^a respectively 20 which are secured between the said members.

Disposed at a point near the inner end of the shaft 24, and freely mounted thereon is a sprocket wheel 27 driven by means of a chain 28 from a sprocket wheel 29 upon the 25 main driving shaft of the labeling machine.

Formed integral with the sprocket wheel 27 is a sleeve 30 provided upon its outer face with clutch teeth 31 designed to engage with a slidable clutch member 32 splined to the 30 said shaft, and designed to be brought into engagement with the said teeth by means of pins carried upon the lower extremities of levers 33 mounted upon a transverse shaft 33^a journaled within the members 11, 11^a, the said 35 pins engaging an annular groove upon the said clutch member, the necessary movement for operating the clutch being imparted to the shaft 33 by means of a hand lever 33^b. 40 34 indicates a shaft running transversely of the members 11, 11^a, and carried in bearings such as 35 mounted upon the respective members.

Mounted upon the outer end of the shaft 24 is a bevel pinion 36 which engages with a second bevel pinion 37 upon the shaft 34 to thereby transmit motion to this shaft. 38 45 indicates a crank arm mounted upon the forward end of shaft 34, and provided at its outer end with a revolvably mounted disc 39 having thereon an eccentrically mounted pin 41 to which is pivoted, by means of a body 42, one end of a connecting rod 43, the other end of which is connected to the outer end of a lever 44 which is freely mounted at its inner 50 end upon the shaft 13.

Mounted upon the forward end of shaft 13 is a ratchet wheel 45, with which is designed to engage a pawl 46 carried at the outer end of the connecting rod 43, the arrangement 60 being such that an intermittent motion is transmitted to the conveyor of sufficient extent to cause each bottle to be presented to the labeling machine, and to remain there for sufficient time to allow the labeling operation 65 to be performed.

47 (Fig. 4) indicates a ratchet wheel mounted upon the rear end of shaft 13, and 70 48 indicates a bell crank lever pivotally mounted upon the member 11^a, and provided at its inner end with a roller 50 which engages with a cam 50^a mounted at a point near the rear end of the shaft 34, and which cam is of such contour that the lever 48 is rocked to periodically cause a pin 51, disposed upon the outer end of the lever, to be brought into engagement with one of the teeth of the ratchet wheel 47 to lock the conveyor whilst each labeling operation is in progress.

52 indicate wipers all of which may be of one design or of various designs, as shown in Fig. 1, depending on the nature or outline of the particular labels to be wiped or pressed. Said wipers are composed of sponge, rubber, or other suitable material, and carried by means of bodies 53 disposed upon the lower 80 ends of rods 54 carried by the plate 55, and progressively press the label on each bottle as it passes through the pressing section.

Mounted upon the member 11^a is a frame 56 comprising vertical members 57, 58 connected at their upper and lower ends by cross members 59, 59^a respectively.

60 indicates a horizontally disposed lever pivotally mounted at its outer end upon the rear end of the shaft 13, and provided at a point between its inner and outer ends with a vertical limb 60^a, the upper end of which is provided with a roller 61, which engages with a cam 62 mounted upon the shaft 34.

The inner end of the lever 60 is connected by means of a link 63, and a body 64 to the lower end of a vertically disposed rod 65 journaled in bearings 65^a, 65^b formed integral with the respective cross members 59, 59^a of the frame 56, and located at points midway of the length of these members.

Mounted upon the upper portion of the rod 65 is a horizontally disposed body 66, the ends of which engage vertically disposed guide rods 67, 68, carried by means of lugs 69 formed upon the members 57, 58 of the frame 56, the body 66 being designed to reciprocate with the rod 65 and to carry a horizontally disposed U shaped body 70, the limbs of which engage with lugs 71 upon the plate 55, and thus serve to support the same.

The contour of the aforementioned cam 62 is such that motion is periodically transmitted through the lever 60 to reciprocate the rod 65, and cause the wipers to be lowered into operative position upon the bottles during the periods when the conveyor is stationary.

The operation of the labeling machine and the conveyor is as follows:—

After the paste roller 5 has passed across the picker blades 3, the picker blades are carried upon the frame 4 up to the underside of the label magazine 2, where the paste upon the said blades causes the lower-most

label in the magazine to adhere to the same.

The picker blades then descend for a certain distance, after which, the picker arm 9 descends between the said picker blades and applies and holds the centre of the label upon the bottle on the conveyor, which has now come to rest, whilst the picker blades rise leaving the label upon the bottle. The picker arm then rises, and the conveyor moves the labeled bottle along and the next bottle into position for labeling. The labeled bottles are successively brought by the conveyor into position beneath the wipers 52 which operate as previously described.

Claims:

1. Apparatus for applying labels to articles comprising a plurality of pads having surfaces contoured to agree with the surface to which the label has been applied, supports for said pads, rods upon said support, a horizontally disposed bar to which said rods are connected, a vertically disposed slide carrying said bar, guides for said slide, means intermittently operating said slide to cause the label engaging pads to press upon the labels and to be removed therefrom, a horizontally disposed endless flexible body, supports carried by said body for said articles, and means intermittently operating said body to bring the articles into position for the pads to operate and to remove them after the operation has been completed.

2. Apparatus for applying labels to articles, comprising a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting articles having the labels applied thereto, a shaft disposed longitudinally of the frame, means for driving said shaft, a second shaft disposed at a right angle to said first shaft, gearing drivingly connecting said first and second shaft, means drivingly connecting said second shaft with one of the chain wheel shafts whereby an intermittent motion is transmitted to the chains carrying the articles, a plurality of elements adapted to engage the labels upon the articles, means for bringing said elements into contact with said labels whilst the chains are stationary and removing them therefrom when their operation is completed.

3. Apparatus for applying labels to articles, comprising a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting

articles having the labels applied thereto, a shaft disposed longitudinally of the frame, means for driving said shaft, a second shaft disposed at a right angle to said first shaft, gearing drivingly connecting said first and second shafts, means drivingly connecting said second shaft with one of the chain wheel shafts whereby an intermittent motion is transmitted to the chains carrying the articles, a plurality of elements adapted to engage the labels upon the articles, and means for bringing said elements into contact with said labels whilst the chains are stationary and removing them therefrom when their operation is completed, and means for locking the chains against movement whilst the various labeling elements are in operation.

4. Apparatus for applying labels to articles, comprising a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting articles having the labels applied thereto, a shaft disposed longitudinally of the frame, means for driving said shaft, a second shaft disposed at a right angle to said first shaft, gearing drivingly connecting said first and second shafts, means drivingly connecting said second shaft with one of the chain wheel shafts whereby an intermittent motion is transmitted to the chains carrying the articles, a ratchet wheel mounted upon one of the chain wheel shafts, a bell-crank lever mounted upon one of the longitudinal members of the frame of the machine, a roller at one end of said bell crank lever, a pin upon the other end of said lever, a cam upon the second shaft engaging said pin, said pin being caused by said cam to engage the ratchet teeth and to hold the chains stationary during the operation of the labeling elements, a plurality of elements adapted to engage the labels upon the articles, means for bringing said elements into contact with said labels whilst the chains are stationary and removing them therefrom when their operation is completed.

5. Apparatus for applying labels to articles, comprising a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting articles having the labels applied thereto, a shaft disposed longitudinally of the frame, means for driving said shaft, a second shaft disposed at a right angle to said first shaft, gearing drivingly connect-

ing said first and second shafts, means driv-
ingly connecting said second shaft with one
of the chain wheel shafts whereby an inter-
mittent motion is transmitted to the chains
5 carrying the articles, vertically disposed
members, a slide carried by said members, a
horizontally disposed member carried by
said slide and supporting a plurality of ele-
ments adapted to engage the said labels, and
10 means operable from the second shaft to
reciprocate the carriage in the vertical plane
to bring the labeling elements into and out
of contact with said labels.

6. Apparatus for applying labels to ar-
15 ticles, comprising a frame embodying side
members, shafts extending transversely of
said side members and disposed adjacent
each end thereof, two suitably spaced chain
wheels upon each shaft, endless chains en-
20 gaging said chain wheels, means for main-
taining said chains in the desired spaced re-
lationship, means carried by said chains for
supporting articles having the labels ap-
plied thereto, a shaft disposed longitudinally
25 of the frame means for driving said shaft,
a second shaft disposed at a right angle to
said first shaft, gearing drivingly connecting
said first and second shafts, means drivingly
connecting said second shaft with one of the
30 chain wheel shafts whereby an intermittent
motion is transmitted to the chains carrying
the articles, a ratchet wheel mounted upon
one of the chain wheel shafts, a bell-crank
lever mounted upon one of the longitudinal
35 members of the frame of the machine, a roller
at one end of said bell crank lever, a pin upon
the other end of said lever, a cam upon the
second shaft engaging said pin, said pin
being caused by said cam to engage the
40 ratchet teeth and to hold the chains station-
ary during the operation of the labeling ele-
ments, vertically disposed members, a slide
carried by said members, a horizontally dis-
posed member carried by said slide, a plu-
45 rality of elements adapted to engage the
labels upon the articles, a horizontally dis-
posed lever pivoted upon one of the chain
wheel shafts, a roller on said lever, a cam upon
the second shaft engaging said roller, a rod
50 connected to the slide, and a connection be-
tween said lever and said rod whereby said
slide is intermittently lowered and raised.

7. In a labeling machine of the type speci-
55 fied; a plurality of elements adapted to en-
gage the labels previously applied to the
articles, means for reciprocating said elements
in a plane perpendicular to the longitudinal
axes of said articles to cause said elements to
60 engage the labels and to be removed there-
from, means for supporting said articles
means intermittently moving said supports in
a plane at a right angle to the line of move-
ment of the label engaging elements to bring
65 the articles into position to be operated upon
by the labeling machine and by the label ap-

plying elements, and remove them after the
operation has been completed.

8. In a labeling machine of the type speci-
70 fied, a plurality of pads having surfaces con-
toured to agree with the surface to which the
label has been applied, supports for said pads,
rods upon said support, a horizontally dis-
posed bar to which said rods are connected, a
75 vertically disposed slide carrying said bar,
guides for said slide, means intermittently
operating said slide to cause the label engag-
ing pads to press upon the labels and to be
removed therefrom, a horizontally disposed
80 endless flexible body, supports carried by said
body for said articles, and means intermit-
tently operating said body to bring the ar-
ticles into position for the pads after the
articles have passed the labeling machine and
the label applying elements, and to operate
85 and to remove them after the operation has
been completed.

9. In apparatus for applying labels to ar-
90 ticles, the combination of a labeling machine
of the type specified, a frame embodying side
members, shafts extending transversely of
said side members and disposed adjacent each
end thereof, two suitably spaced chain wheels
95 upon each shaft, endless chains engaging said
chain wheels, means for maintaining said
chains in the desired spaced relationship,
means carried by said chains for supporting
articles and presenting them to the labeling
100 machine, a shaft disposed longitudinally of
the frame, means for driving said shaft, a sec-
ond shaft disposed at a right angle to said
first shaft, gearing drivingly connecting said
first and second shafts, means drivingly con-
105 nnecting said second shaft with one of the
chain wheel shafts whereby an intermittent
motion is transmitted to the chains carrying
the articles, a plurality of elements adapted
110 to engage the labels previously applied by the
labeling machine, means for bringing said
elements into contact with said labels whilst
the chains are stationary and removing them
therefrom when their operation is completed.

10. In apparatus for applying labels to ar-
115 ticles, the combination of a labeling machine
of the type specified, a frame embodying side
members, shafts extending transversely of
said side members and disposed adjacent each
end thereof, two suitably spaced chain wheels
120 upon each shaft, endless chains engaging said
chain wheels, means for maintaining said
chains in the desired spaced relationship,
means carried by said chains for supporting
articles and presenting them to the labeling
125 machine, a shaft disposed longitudinally of
the frame, means for driving said shaft, a sec-
ond shaft disposed at a right angle to said
first shaft, gearing drivingly connecting said
first and second shafts, means drivingly con-
130 nnecting said second shaft with one of the
chain wheel shafts whereby an intermittent
motion is transmitted to the chains carrying

the articles, a plurality of elements adapted to engage the labels previously applied by the labeling machine, means for bringing said elements into contact with said labels whilst the 5 chains are stationary and removing them therefrom when their operation is completed, and means for locking the chains against movement whilst the various labeling elements are in operation.

10 11. In apparatus for applying labels to articles the combination of a labeling machine of the type specified, a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by 15 said chains for supporting articles and presenting them to the labeling machine, a shaft disposed longitudinally of the frame, means for driving said shaft, a second shaft disposed at a right angle to said first shaft, 20 gearing drivingly connecting said first and second shafts, means drivingly connecting said second shaft with one of the chain wheel shafts whereby an intermittent motion is transmitted to the chains carrying the articles, 25 a ratchet wheel mounted upon one of the chain wheel shafts, a bell-crank lever mounted upon one of the longitudinal members of the frame of the machine, a roller at one end of said bell crank lever, a pin upon the 30 other end of said lever, a cam upon the second shaft engaging said pin, said pin being caused by said cam to engage the ratchet teeth and to hold the chains stationary during the operation of the labeling elements, 35 40 45

40 45 50 55 60 65 70 75 80 85 90 95 100 105 110 115 120 125 130

elements, a plurality of elements adapted to engage the labels previously applied by the labeling machine, means for bringing said elements into contact with said labels whilst the chains are stationary and removing them therefrom when their operation is completed.

12. In apparatus for applying labels to articles, the combination of a labeling machine of the type specified, a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting articles and presenting them to the labeling machine, a shaft disposed longitudinally of the frame, means for driving said shaft, a second shaft disposed at a right angle to said first shaft, gearing drivingly connecting said first and second shafts, means drivingly connecting said second shaft with one of the chain wheel shafts whereby an intermittent motion is transmitted to the labeling elements, a ratchet wheel mounted upon one of the chain wheel shafts, a bell-crank lever mounted upon one of the longitudinal members of the frame of the machine, a roller at one end of said bell crank lever, a pin upon the other end of said lever, a cam upon the second shaft engaging said pin, said pin being caused by said cam to engage the ratchet teeth and to hold the chains stationary during the operation of the labeling elements, vertically disposed members, a slide carried by said members, a horizontally disposed member carried by said slide, a plurality of elements adapted to engage the labels upon the articles, a horizontally disposed lever pivoted upon one of the chain wheel shafts, a roller on said lever, a cam upon the second shaft engaging said roller, a rod connected to the slide and a connection between said lever and said rod whereby said slide is intermittently lowered and raised.

chains carrying the articles, vertically disposed members, a slide carried by said members, a horizontally disposed member carried by said slide and supporting a plurality of elements adapted to engage the said labels, and means operable from the second shaft to reciprocate the carriage in the vertical plane to bring the labeling elements into and out of contact with said labels.

13. In apparatus for applying labels to articles, the combination of a labeling machine of the type specified, a frame embodying side members, shafts extending transversely of said side members and disposed adjacent each end thereof, two suitably spaced chain wheels upon each shaft, endless chains engaging said chain wheels, means for maintaining said chains in the desired spaced relationship, means carried by said chains for supporting articles and presenting them to the labeling machine, a shaft disposed longitudinally of the frame, means for driving said shaft, a second shaft disposed at a right angle to said first shaft, gearing drivingly connecting said first and second shafts, means drivingly connecting said second shaft with one of the chain wheel shafts whereby an intermittent motion is transmitted to the chains carrying the articles, a ratchet wheel mounted upon one of the chain wheel shafts, a bell-crank lever mounted upon one of the longitudinal members of the frame of the machine, a roller at one end of said bell crank lever, a pin upon the other end of said lever, a cam upon the second shaft engaging said pin, said pin being caused by said cam to engage the ratchet teeth and to hold the chains stationary during the operation of the labeling elements, vertically disposed members, a slide carried by said members, a horizontally disposed member carried by said slide, a plurality of elements adapted to engage the labels upon the articles, a horizontally disposed lever pivoted upon one of the chain wheel shafts, a roller on said lever, a cam upon the second shaft engaging said roller, a rod connected to the slide and a connection between said lever and said rod whereby said slide is intermittently lowered and raised.

In testimony whereof I have hereunto set my hand.

PERCIVAL JOHN PURDY.
